UNITED STATES PATENT OFFICE.

ROBERT D. SIMPSON, OF COLUMBUS, OHIO.

CLOSURE DEVICE.

Application filed February 13, 1926. Serial No. 88,120.

My invention relates broadly to a closure device and, more particularly, to a means for sealing the discharge opening of a collapsible dispensing tube.

My invention provides a device which may be secured to the discharge neck of a collapsible dispensing tube or other container and embodies a closure of such construction that it may be operated, without detachment, to open and close the discharge opening and tightly seal it against accidental opening and the ensuing evaporation of volatile constituents and hardening of the tube contents.

One object of my invention is the provision of a closure device which may be employed to replace the usual screw cap but which embodies a closure of such construction that the container outlet may be opened to permit removal of the contents without completely removing any part of the closure means.

Another object of my invention consists in the provision of a closure structure which is such that it must ride over a high point of resistance into and out of closing position and which will, at the same time, effect a sealing closure when it moves into closing position. The closure structure is such that it is readily applied or removed from the container.

Another feature of my invention consists in the provision of a mouth-piece of non-metallic material. This mouth-piece is also, preferably, detachably applied and applicable to standard containers.

Another object of my invention is the provision of an outlet closure which may be removed from one container and placed upon another container.

One embodiment of my invention is illustrated in the accompanying drawings wherein similar characters of reference designate corresponding parts and wherein:

Figure 1 is a fragmentary vertical sectional view through a collapsible dispensing tube showing my novel closing device as applied thereto.

Figure 2 is a vertical sectional view through my novel container closing device showing the closure in different positions with reference to the outlet opening thereof.

Figure 3 is a vertical sectional view showing the arrangement of the extensions

whereby the closure device is pivoted to the cap.

Figure 4 is a horizontal sectional view taken on line 4—4 of Figure 3 and

Figure 5 is a fragmentary perspective view showing my invention in association with a collapsible dispensing tube.

In the drawings, one illustrative embodiment of my invention is shown in association with a collapsible dispensing tube 1 which may be formed with a tapered reduction 2 and an externally threaded discharge neck 3 provided with an opening 4. Obviously, my invention is not limited to use with a collapsible dispensing tube, because its various features, as hereafter more particularly described, are broadly applicable to any container wherein a closure of this nature is desired.

The cap 5 which is preferably manufactured from colored bakelite, durez, karo-lith, or other suitable non-corroding material, may be internally threaded and adapted to engage with the externally threaded discharge neck 3 as shown in Figure 1. This cap may be provided with an opening 6 which may be of any desired shape and which is adapted to register with the opening 4 formed in the discharge neck 3 to form an outlet for the material contained in tube 1.

For sealing the opening 6, I have provided a closure device 7 which may be pivoted to the cap 5 by means of suitable extensions 8. These extensions 8 may be formed with hook portions 9 which engage in oppositely disposed openings 10 formed in the cap 5 adjacent its bottom. The inner faces of openings 10 may be beveled to form a bearing surface 11 for the hook portions 9 of extensions 8.

This prevents them from interfering with the removal or replacement of the cap 5. It will be noted that the openings 10 are effectually closed against disengagement of the hook portions 9 of extensions 8 by the abutment of the bottom of cap 5 against the reduced portion 2 of tube 1 as best shown in Figures 1 and 5.

The closure device 7 may be formed with a cup portion 12 which is adapted to contain a yieldable pad 13 of cork or other suitable material. This pad 13 is adapted to yield or compress and flex centrally into the space 14 between it and the top of closure device

7 when said closure device is oscillated in either direction over the edge or corner of the cap 5 in the manner illustrated in full lines in Figure 2. The extensions 8 of closure 5 7 may be formed of resilient material and bowed to allow a slight elongation as the pad 13 passes over the shoulder 15 formed on the cap 5, and, if so bowed, it is obvious that a slight contraction, sufficient to retain 10 the closure device 7 in opened or closed position, will occur when said closure device is moved to opened or closed position.

In operation, the closure device 7 may be oscillated in either direction by the thumb 15 of one hand while the tube 1 is held by the fingers of the same hand. The top of the closure device may be formed with suitable projections to prevent slippage of the thumb when opening or closing the opening 6. The 20 resiliency of the extensions 8, combined with the yieldability of pad 13 and the relatively flat top of cap 5, will be sufficient to maintain the closure device over opening 6. In other words, the resiliency of the extensions 25 8 and pad 13, together with obstruction to material movement which is offered by the edge or corner of cap 5, will hold the said pad against the flat top of cap 5 and prevent accidental opening of the outlet 6.

30 From the foregoing description, it will be obvious that my invention provides a simple and effective closure which may be removed from one tube and placed upon another, which will prevent accidental opening of the 35 outlet, and which will not discolor the tube contents or permit hardening of same due to the evaporation of volatile ingredients.

Having thus described my invention, what I claim is:

40 1. As an article of manufacture, a tooth paste container having a cap provided with a discharge orifice made of a substantially rigid non-corrosive and non-metallic material, and a closure member adapted to be moved over and away from said orifice.

50 2. As an article of manufacture, a tooth paste container having a cap provided with a discharge orifice made of a substantially rigid non-corrosive and non-metallic material, and a resilient closure member adapted to be moved over and away from said orifice.

55 3. The combination of a collapsible dispensing tube having a discharge neck, a non-metallic apertured cap adapted to engage with said neck, an oscillatable closure device having resilient extensions pivoted to

said cap and a yieldable pad carried by said closure device for maintaining it in closed position with reference to said aperture.

4. In combination, a container having a 60 discharge neck, an apertured cap adapted to engage with said neck, a closure device pivoted to said cap by flexible extensions and a yieldable pad carried by said closure device for assisting said flexible extensions in maintaining it in opened or closed position with reference to said aperture.

5. The combination of an apertured substantially flat-topped cap, means pivoted to 70 said cap by stationary pivots and adapted to be oscillated about such pivots to open and close said aperture, said means embodying resilient parts for maintaining it in contact with the flat top of said cap.

6. In combination, a container having a 75 discharge neck, a substantially flat-topped apertured cap adapted to engage with said neck and an oscillatable closure device having extensions pivoted to said cap and carrying a yieldable pad the resiliency of which 80 tends to hold said closure device in opened or closed position with reference to said aperture.

7. A device of the class described comprising a substantially flat topped apertured 85 cap having means for attaching same to a receptacle, a closure device pivoted to and movable about the said cap for opening and closing said aperture and a resilient pad carried by said closure device and expansible 90 against the flat top of said cap for frictionally maintaining said closure device in closed position with relation to said aperture.

8. A device of the class described comprising 95 a substantially flat-topped apertured cap and a closure device pivoted to said cap by bow shaped resilient members the resiliency of which holds said closure device against the flat top of said cap and prevents accidental uncovering of said aperture.

5. In combination, a collapsible tube container having a discharge neck provided with an aperture, an oscillatable closure device pivoted to said neck by flexible extensions, and a yieldable pad carried by said closure device for assisting said flexible extensions in maintaining it in open or closed position with reference to said aperture.

In testimony whereof I hereby affix my 110 signature.

ROBERT D. SIMPSON.
